UNITED STATES PATENT OFFICE.

FLOYD L. SCOTT, OF HOUSTON, TEXAS, ASSIGNOR TO HUGHES TOOL COMPANY, OF HOUSTON, TEXAS, A CORPORATION OF TEXAS.

REAMER FOR WELLS.

Application filed February 12, 1927. Serial No. 167,620.

My invention relates to reamers of the roller type, such as are employed in well drilling to preserve or to increase the gauge of the hole drilled by the bit.

5 It is an object of the invention to provide a reamer which is strong and substantial and capable of withstanding hard usage without injury.

10 It is my aim to so mount the reaming rollers that they will be easy to insert and remove from position in the head of the reamer, and not liable to become loose and be dropped from the head, and lost in the well.

15 The construction and arrangement of the cutters, and their means of mounting, forms an important feature of the invention, and this construction will be better understood from a reading of the specification which follows.

20 Referring to the drawing herewith, Fig. 1 is a side elevation of my improved reamer. Fig. 2 is a central vertical section through the reamer, the lower cutter being removed from its pin. Fig. 3 is a transverse section 25 on the plane 3—3 of Fig. 1.

The head of the reamer comprises an elongated block or casting or metal 1, which, as seen in Fig. 3, is somewhat triangular in cross section with three flattened sides 2, and with 30 the corners of the triangle rounded at 3, and adapted to form a mounting for the cutters. The head has an upper shank 4, threaded for attachment to a collar or coupling. Its lower end has a threaded box 5 for attachment to the drill or such pilot as may be used. There is 35 a central axial channel 6, through the head for flushing fluid.

I contemplate the use of more than one stage of reaming cutters on the head, although but one may be used. Two stages are 40 shown in the drawing, the upper cutter being adjacent the upper end, and the lower one spaced downwardly therefrom the desired distance. There are thus two cutters in vertical alignment at each of the three corners 45 of the head.

The head is formed with sockets 7 in the same to receive the cutters 8 which are approximately cylindrical in shape. Cutter-pin-receiving sockets 9 are formed in the 50 ends of said recesses remote from the adjacent cutter. The inner ends of the socket 7

have pin receiving openings 10, opening from the recess into a channel or pocket 11, between the cutters.

55 Said channel 11 is wide enough to receive the heads 12 of the cutter pins 13 and long enough so that the pin may be inserted therefrom into the openings 10, through the cutters 8, and into the recess 9. The heads 12 of the pins 13 are made eccentric to the axis of the said pins and said heads fit within the channel 11 so that they may not rotate. Washers 14 are employed at each end of each cutter 8 to furnish a bearing surface for the 60 cutter.

65 The cutter pins 13 are locked from removal by means of a locking block 15 shaped to fit the pocket 11, when the cutter pins are in position, and to bear against the heads of the pins and hold them from longitudinal movement. The blocks 15 are held in position by screws 16 extending through the blocks into the reamer head. The screw heads have diametrical openings therein to 70 receive cotter pins 17 which fit within small depressions 18 in the block and prevent rotation of the screws.

75 The formation of the cutter pins and the means of locking them in position enable the 80 cutters to be easily and quickly changed when desired and also guard positively against the accidental removal of the cutters during the operation of the reamer. The use of three cutters in each stage provides a three point 85 contact with the wall of the hole tending to steady the tool. The body of the reamer is also held straight within the hole by its elongated shape bearing at both ends against the walls of the well. The flattened sides of 90 the head allow space in the well for the passage of flushing fluid without difficulty.

I claim:

1. In a reamer, a head having cutter-receiving recesses aligned longitudinally thereof, and a pocket of shallower depth than said recesses between said recesses, cutter pins adapted to be inserted into said recesses from said pocket, the heads of said pins being eccentric on said pins and adapted to fit said 95 pocket to prevent rotation of said pins, cutters on said pins and means between adjacent pins to hold them from removal.

100 2. A cutter including a head having sep-

- arate upper and lower cutter recesses with a
pocket in said head between said recesses, cutter
pins adapted to be inserted from said
pocket longitudinally through said recesses,
heads on said pins, within said pocket, cutters
on said pins within said recesses, a single
block fitting within said pocket to bear
against said heads and hold them in position,
and means to hold said block in said pocket.
- 5 3. A cutter including a head having sep-
arate upper and lower cutter recesses with a
pocket in said head between said recesses,
cutter pins adapted to be inserted from said

pocket longitudinally through said recesses,
said pins having a bearing at both ends in 15
said head, heads on said pins, within said
pocket, cutters on said pins within said re-
cesses, a single block fitting within said
pocket to bear against said heads and hold
them in position and means to hold said block 20
in said pocket.

In testimony whereof, I hereunto affix my
signature, this the 4th day of February A. D.
1927.

FLOYD L. SCOTT.
